UNITED STATES PATENT OFFICE.

GEORGE M. BEARD, OF WARSAW, INDIANA.

EXHAUST-VALVE MECHANISM FOR EXPLOSIVE-ENGINES.

No. 857,149.

Specification of Letters Patent.

Patented June 18, 1907.

Application filed January 17, 1905. Serial No. 241,491.

To all whom it may concern:

Be it known that I, GEORGE M. BEARD, a citizen of the United States, residing at Warsaw, in the State of Indiana, have invented 5 new and useful Improvements in Exhaust-Valve Mechanism for Explosive-Engines, of which the following is a specification.

This invention has relation to exhausts for hydrocarbon gas engines and it consists in 10 the novel construction and arrangement of its parts as hereinafter shown and described.

The object of the invention is to provide exhausts for the character of engines as indicated, the parts of the exhaust being so arranged that when the working piston arrives 15 at the end of the outward stroke a port is opened which permits the gas under pressure to enter a chamber behind a piston head located therein, in such a manner as to move 20 the said piston head and open the exhaust valve whereby the burned charge in the engine cylinder may be expelled by the working piston on its instroke. The said working piston is provided at a certain point with an 25 adjustable valvular appliance which at the end of the instroke of the working piston puts the said chamber in communication with the exhaust so as to allow the outlet port of the engine cylinder to close.

30 In the accompanying drawing, the figure is a longitudinal sectional view of a hydrocarbon engine showing an exhaust valve attached thereto.

The engine consists of the cylinders 1 and 35 2, in which are adapted to reciprocate the pistons 3 and 4, respectively. The inner ends of the pistons 3 and 4, are attached to the yoke 5. The sliding block 6, is located 40 within said yoke and the crank shaft 7, passes through said sliding block. The housing 8, connects the inner ends of the cylinders 1 and 2, together and incloses the yoke 5. Each of the cylinders 1 and 2 is provided at its end with a sparking plug opening 9, and each of 45 the said cylinders is also provided with a gas inlet port 10, which is normally closed by a valve 11. A passage 12, leads down from the outer end of each of the cylinders 1 and 2, and communicates by means of an opening 50 13, with exhaust port 14. The valve 15, is adapted to close against the opening 13. The stem 16, of said valve 15, extends into the chamber 17. A piston 18 is located in the chamber 17, and a coil spring 19, is interposed between the piston 18, and the end

wall of the chamber 17, and surrounds the stem 16. The passage 20, connects one end of the chamber 17, with the interior of the cylinder, while the passage 21, enters the cylinder at one end and the exhaust outlet 14, at its other end. Each of the pistons 3 and 4, is provided with a groove 22, which at the innermost position of the said pistons in its respective cylinder passes over the upper ends of the passages 20 and 21, and connects 65 the same together in a manner as shown by the position of the piston 4, of Fig. 1, of the drawing.

The operation of the device is as follows:— Presuming that the parts are in the position 70 as shown in the figure, and the pistons 3 and 4, are about to move in the direction as indicated by the arrow, as the piston 4, moves within the cylinder 2, the charge of air and gas is drawn into the said cylinder 2, through 75 the inlet port 10. When the piston 4, arrives at the end of the stroke, it immediately begins to move in the opposite direction and compresses the charge drawn into the cylinder 2. The said charge is ignited at the 80 proper time and the piston 4, again moves in the direction as indicated by the arrow. When the end of the piston 4, passes over the passage 20, a part of the product of combustion enters the said passage and passes into 85 the chamber 17, behind the piston 18, thereof. The said piston 18, moves in the chamber 17, and through the valve stem 16, the valve 15, is moved away from the opening 90 13. Thus the burned gases from the cylinder 2, may pass down through the passage 12, through the opening 13, and out through the exhaust outlet 14. As the piston 4, moves toward the head of the cylinder 2, the valve 15, is held open by the burned gases 95 confined in the chamber 17 behind the piston 18 until the groove 22 comes over the upper ends of the passages 20 and 21, when the gases confined in the chamber 17, behind the piston 18, pass up through the passage 20, through the groove 22, and down through the 100 passage 21, into the exhaust outlet 14. As the said gases pass out the spring 19, moves the piston 18, back and closes the valve 15, against the opening 13, when the operation 105 above described is repeated.

As illustrated in chamber 17, under the cylinder 1, the wall of said chamber 17, may be provided with an opening 23, which leads directly from said chamber into the passage 110

21. The said opening 23, is normally closed by the piston 18, but when the said piston is moved by the gases entering the chamber 17, as above described, the opening 23, is uncovered and part of the gases located behind the piston 3, may pass directly through said opening 23, into the passage 21.

As shown in the drawing the piston 3, is provided in its side with a longitudinal adjustable section 24, which is provided with a groove 22, shown in the cylinders 3 and 4, of the figure. This section 24, may be adjusted back or forth by loosening the bolts 25, which secure it to the piston 3, and by so doing the groove 22, may be moved to accommodate high or low speed engines. It is understood that the said section 24, may be so located as to cause the groove 22, to pass over the ends of the passages 20 and 21, before the working piston arrives at the extreme end of its exhaust stroke so as to give more time for the gases back of the piston 18, to escape through the passages 20 and 21.

Having described my invention what I

claim as new and desire to secure by Letters 25 Patent is:—

In combination with an engine cylinder having inlet and outlet ports and a reciprocating piston, a chamber located adjacent said cylinder and communicating with the same by a passage which opens into the cylinder at or near the piston's outstroke, a piston located in said chamber and adapted to be moved by the pressure of the explosion gases and thereby open the cylinder outlet at the end of the working piston's outstroke, and an adjustable valvular appliance moving with the working piston which at the end of the instroke puts the said chamber in communication with the exhaust, so as to allow the outlet port valve to close.

In testimony whereof I affix my signature, in presence of two subscribing witnesses.

GEORGE M. BEARD.
